UNITED STATES PATENT OFFICE.

EDWARD PORTER, OF PERRY, FLORIDA, ASSIGNOR OF ONE-HALF TO JAMES L. WEEKS,
OF PERRY, FLORIDA.

PORTABLE ELECTRIC GRINDING AND POLISHING LATHE.

1,326,091.

Specification of Letters Patent. Patented Dec. 23, 1919.

Application filed June 20, 1919. Serial No. 305,578.

To all whom it may concern:

Be it known that I, EDWARD PORTER, a citizen of the United States, residing at Perry, in the county of Taylor and State of Florida, have invented certain new and useful Improvements in Portable Electric Grinding and Polishing Lathes, of which the following is a specification.

This invention relates to grinding and 10 polishing machines for metal curved surfaces, and pertains especially to a portable electrically operated machine for operating, grinding and polishing wheels of various character.

15 The object of the invention is to provide a portable lathe machine carrying an electric motor for revolving the machine during a grinding and polishing operation by suitable grinding and polishing wheels, or other devices capable of being applied to and operated by the machine.

20 A further object of the invention is to provide a portable machine adapted to be applied to inner and outer curved surfaces 25 of crank pins, cylinders and the like for truing the same by rotating suitable implements during the revolution of the machine either upon the inside or outside of the article or device, against which such implements 30 are operated.

35 A still further object of the invention is to provide a portable motor machine having planetary motion, and comprising novel and peculiar means or devices of simple character for applying the machine to various curved surfaces for grinding, truing and polishing such surfaces.

40 Various other objects, advantages and improved results are attainable by reason of the construction, operation and adaptability of the machine, as will be hereinafter fully described.

45 In the accompanying drawings forming part of this application:

Figure 1 is an end view showing the application of the invention to a crank shaft pin.

Fig. 2 is a side elevation showing the same application.

50 Fig. 3 is a longitudinal sectional view showing the application of the machine without the motor,

Fig. 4 is a detail sectional view taken on the line 4—4 Fig. 3.

Fig. 5 is a detail perspective view of the 55 coupling yoke.

Fig. 6 is a detail perspective view of the coupling member having flanges for suspending a counterbalance and for mounting a motor.

Fig. 7 is a sectional view showing the application of the machine to a cylinder.

Fig. 8 is a sectional view of automobile cylinders showing the application of this invention thereto.

The same reference characters denote the same parts throughout the several views of the drawings.

I am aware of the various apparatus and machines intended for the same purposes as 70 my machine, but such apparatus and machines embody many features, inconveniences and expense of the same which are avoidable in and by my machine, and such machines have been found to be incapable of 75 such universal application and results as are attainable in and by my machine, as will be hereinafter disclosed.

In carrying out my invention I employ a central shaft or rod 1, one end of which 80 is screw-threaded to fit the usual screw socket 2 in the pin 3 of a crank shaft 4 and other similar devices, such as cross head pins and the like, to be trued by grinding and polishing. The other end of the shaft 85 or rod 1 has a square screw-thread and an ordinary thread for a nut 5. Said shaft or rod and nut afford means for attaching the various members or parts of the machine to the article to be ground, as will now be 90 explained. After the rod 1 has been attached to the article to be ground, as the pin 3, a mounting or foundation member 6, having a central longitudinal bore 7 for the rod 1, is secured against the face of the 95 pin 3 by the nut 5. The mounting 6 has a key-way 8 for a key 9 on the inner periphery of a gear wheel 10 slidably lengthwise on the member 6, and said wheel is provided with flanges forming an annularly grooved hub 11, for a pair of prongs 12 of a coupling yoke 13. A split sleeve 14 having suitable 100 clamping bolts, is slidably mounted on the member 6, and the yoke is bolted to the

sleeve, whereby the gear 10, the sleeve 14 and the yoke are connected so as to slide in unison on the member 6 during the revolution of these elements in a grinding or 5 polishing operation. The head 18 of the yoke is slidable over the square thread of the rod 1 during said revolution only when the yoke stud 19 is in mesh with said thread. The stud 19 works through and is controlled 10 by a spiral spring 20 having one end abutting against the upper wall 21 of a pocket 22 in the yoke head, and the other end works against the enlarged end or flange 23 of the stud which has head grooves 24 for meshing 15 with ribs 25 on the yoke head 18. The function of the spring is to keep the stud in mesh with the square thread of the rod 1, until the stud is lifted by pulling it out of mesh and turning it so that the stud grooves will 20 engage the ribs 25 crosswise, whereby the stud is held in raised position. Obviously by turning the stud so that the grooves and ribs will mesh, the spring 20 pulls the stud into mesh with the rod screw. 25 The base of the motor 26 is bolted to the sleeve flange 16, and the motor is adjusted vertically by a hand screw 27 to set the wheel 28, which is secured to one end of the shaft 29, in grinding position on the pin 3, 30 for longitudinal movement by a like movement of the motor. The other end of the motor shaft 29 operates a reducing gear housed at 30 and operating a shaft 31 journaled in bearings 32 of the sleeve 14 and 35 having a worm 33 meshing with the gear wheel 10, for revolving the whole machine on the fixed shaft or rod 1, during rotary movement of a grinding, or polishing wheel by the motor, and during longitudinal movement 40 of the whole machine when the stud 19 is in mesh with the square thread of the rod or shaft 1.

The motor is supplied with electric current by wires 34 attached thereto and carried by the yoke 13, and by a pair of split collector rings 35 loosely clamped to an annular flange 36 of the yoke head 18. In order to counterbalance the machine I attach an arm 1^a to a flange 16^a projecting 45 from the sleeve 14, and provide said arm with a weight 3^a adjustable thereon. Obviously this arm may be shorter and the weight heavier if necessary to permit the operation of the machine with respect to 50 certain devices or work, especially with respect to cylinders wherein the machine is operated. It will be observed that the rod or shaft 1, is used for anchoring or attaching and centralizing the machine with respect to the article to be ground, and also affords means for feeding the machine transversely during its revolution, and during 55 rotary movement of the motor which revolves and feeds the machine.

60 Referring to Fig. 7, the machine is shown

as applied to a steam engine cylinder 37 for grinding and polishing the inner periphery thereof, and in order to make such application, I secure the ends of a spanner 38 to one end of the cylinder, and provide the 70 spider head 39 with a tubular extension 40 through which the shaft 41 extends and by means of which said shaft is centralized relative to the cylinder 31. The projecting ends of the shaft 41 may be journaled in suitable supports, and the whole machine, as hereinbefore described, may be operated within this cylinder for grinding, and polishing the inner wall thereof.

Referring to Fig. 8 of the drawings, the 80 same machine in its entirety may be applied to automobile head cylinders 42 by means of a frame 43 adapted to be bolted to the face of the cylinders, and mounting the motor 44 on the frame 43 so as to be shifted from one 85 to another of the cylinders for grinding and truing them. Obviously there must be a lengthened or longer motor shaft 45 for this application of the machine, and sufficient space is provided between the face of the 90 cylinders and the frame 43 to permit the grinding wheel to be slid, in said shifting of the machine, from one cylinder to another without removing the motor or its shaft until all the cylinders are ground, 95 whereupon the frame 43 is readily detached and removed.

Obviously the compactness of the machine is of great advantage in transportation and application either for outside or 100 inside grinding and polishing. The machine is self feeding lengthwise during simultaneous revolution thereof, and of the grinding wheel at a greater velocity than the revolution of the machine, and the machine is not limited in its applications as herein shown and described, but may be used for grinding and truing rocker arm pins of the well known Corliss engines, cross head pins of various engines, valves, and 110 valve bonnets. Therefore I do not wish to be understood as limiting myself in these respects, nor to any particular material and size in the manufacture and practical application of the invention, nor to any particular vertical feed for motor or any particular reducing gearing, but reserve the right to make such changes and variations therein and in the combination of the various parts of the machine as may not be inconsistent with the appended claims.

Having thus described my invention what I claim as new and desire to secure by Letters Patent is:

1. In a grinding machine of the character 125 described, a foundation member, a non-revolving screw shaft upon which said member is loosely mounted, said shaft adapted to be attached to the article to be ground, a motor slidably mounted on and geared 130

with the foundation member for revolving it, and an adjustable feed device connected with the motor and adapted to mesh with the said screw shaft for sliding the motor during the joint revolution of the motor and the foundation member.

2. In a grinding machine of the character described, a fixed shaft having a screw feed portion, a foundation cylinder loosely mounted on the shaft whereby one end of the cylinder is made to engage the article to be ground and the other end forms the only bearing between the cylinder and the shaft for the purpose of alinement with respect to such article, a motor slideable on and geared with the cylinder, and a feed device connected with the motor and meshing with the said screw portion for sliding the motor during the joint revolution of the motor and the cylinder.

3. In a grinding machine of the character described, a foundation member, a fixed shaft upon which said member is mounted and having a feed screw, a gear wheel slidably keyed on said member, a yoke having a head revoluble on said shaft and engaging the wheel hub, a stud adjustable in the yoke head for meshing with said screw, a motor

having a grinding wheel spindle, means connecting the motor with the yoke for feeding the motor transversely, and a reducing gearing connecting the motor with said wheel.

4. In a grinding machine of the character described, a foundation member, a fixed shaft upon which said member is mounted and having a feed screw, a gear wheel slidably keyed on said member, a yoke having a head revoluble on said shaft and engaging the wheel hub, a stud adjustable in the yoke head for meshing with said screw, a sleeve on the foundation member and attached to the yoke, a motor mounted on the sleeve and geared with said wheel for revolving the foundation member; the sleeve and the yoke in unison, and a grinding wheel rotated by the motor during the revolution of the foundation member and during transverse feeding of the yoke and the motor.

In witness whereof I hereunto set my hand in the presence of two witnesses.

EDWARD PORTER.
